UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNORS TO VICKERS LIMITED, OF WESTMINSTER, ENGLAND.

LOADING APPARATUS OF HEAVY GUNS.

1,157,682.

Specification of Letters Patent. Patented Oct. 26, 1915.

Original application filed September 30, 1911, Serial No. 652,192. Divided and this application filed September 29, 1913. Serial No. 792,245.

To all whom it may concern:

Be it known that we, ARTHUR TREVOR DAWSON, knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in Loading Apparatus of Heavy Guns, of which the following is a specification.

This invention relates to the control of the loading apparatus of heavy guns of the kind in which the operating motor is controlled by a valve carried by a part of the mounting that does not move with the gun in elevation.

According to the present invention the rammer motor on the slide frame or loading arm is controlled by a valve also carried by the slide frame or loading arm, the movements of the said valve being under the influence of a hand actuated valve on the gun platform. By these means the motor on the slide frame or loading arm can be controlled independently of the hand actuated valve by the automatic means hereinafter described.

In order that the said invention may be clearly understood and readily carried into effect we will describe the same more fully with reference to the accompanying drawings, in which—

Figure 1 is a diagrammatic side elevation showing our improvements; Fig. 2 is a sectional side elevation of the hand actuated valve and its associated parts on the gun platform and of a cut-off valve carried by the gun slide; and Fig. 3 is a sectional side elevation of a differential valve and its associated parts carried by the loading arm.

A is the gun, A' the slide frame, A² the loading arm, A³ the rammer carried thereby, A⁴ the rammer control hand lever and a² the valve connected thereto.

The rammer A³, which is shown by way of example as of the flexible or chain type, is under the influence of a hydraulic motor A⁰ controlled by a differential valve a carried by the loading arm. The differential ram cylinder of the said valve is connected by a pipe a' with the hand control valve a² of the hand lever A⁴ of the rammer control-

ling mechanism, the cut off valve a³ carried by the gun slide being adapted to coöperate with the rammer A³ and being connected with the reversing cylinder a⁴ on the gun platform by a pipe a⁵. In order to prevent the rammer from leaving the withdrawn position until the gun loading cage C is in alignment with the bore of the gun, and for causing the rammer to automatically perform its first ramming stroke, a spring bolt a⁶ is adapted to coöperate with the stem of the control valve a to lock it in the position 55 to retain the rammer in the withdrawn position. A stop c on the gun loading cage C coöperates with the said spring bolt a⁶ and withdraws it from engagement with the stem of the control valve a as the cage 60 reaches its loading position, whereupon, the hand lever A⁴ having been previously placed to the "ram" position, the valve a will move into the position to cause the rammer to ram the projectile into the gun. The usual locking bolt A⁷ is provided on the loading arm for retaining the loading cage C in position 65 until the rammer has been fully withdrawn.

When the hand lever A⁴ is in the "withdraw" position shown in Fig. 1 and in full 70 lines in Fig. 2, the valve a² supplies pressure fluid to the differential ram cylinder of the valve a and the latter is therefore held in the position shown in Fig. 3 owing to the fact that the pressure on the end of the ram 75 of this valve preponderates over the constant pressure of the fluid supplied to the valve casing by the pipe a^{1x}. When the hand lever A⁴ is moved to the "ram" position shown by chain lines in Fig. 2, the valve a² places the pipe a' to exhaust, and the valve a then tends to move toward the right (by the pressure of the fluid supplied by the pipe a^{1x}) to admit pressure fluid to the rammer motor to effect the ramming stroke 80 of the rammer; this movement is prevented until the spring bolt a⁶ is disengaged as aforesaid. When the hand lever A⁴ is moved to the "withdraw" position, pressure fluid is again admitted by the pipe a' 85 to the differential ram cylinder of the valve a and this valve is thereby moved to the left and reverses the rammer motor. The hand lever A⁴ and the valve a² are automatically moved from the "ram" to the "withdraw" 90 position at the end of the ramming stroke.

by the differential valve a^3 which under the influence of the constant pressure fluid supplied by a pipe a^{5x} tends to move toward the right. This movement of the 5 valve a^3 is prevented by a bell crank lever a^{4x} connected to the valve stem and bearing against the rammer until the last link of the rammer moves clear of the bell crank lever, whereupon the valve a^3 moves 10 toward the right and places the pipe a^5 and the right hand face of the ram in the cylinder a^4 to exhaust; pressure fluid supplied by a pipe a^{5x} to the left hand face of the piston in the cylinder a^4 then moves this 15 ram to the right and in so doing displaces the valve a^2 and the hand lever A^4 to its "withdraw" position, this movement being effected through the lever a^{6x} . When the 20 rammer in consequence performs its withdrawal stroke, the last link thereof displaces the bell crank lever a^{4x} to move the valve a^3 into the position shown in Fig. 2 in which it again admits pressure fluid to the right hand end of the cylinder a^4 ; the 25 ram in this cylinder then moves toward the left until it reaches the position shown by Fig. 2, this movement occurring owing to the fact that the right hand rod of the ram is of smaller diameter than the left hand 30 rod. The ram is normally held in the position shown by a spring catch a^{7x} which is displaced to its disengaging position when the hand lever A^4 is moved to its "ram" position.

35 3. What we claim and desire to secure by Letters Patent of the United States is:—

1. In gun loading apparatus the combination with the slide frame, the rammer actuating motor carried thereby, and the motor control hand lever mounted on a part of the mounting that does not move in elevation, of a control valve carried by the slide frame, and pressure fluid means for actuating said valve from the aforesaid hand lever.
2. In gun loading apparatus, the combination with the slide frame, the rammer actuating motor carried thereby and the motor control hand lever mounted on a part of the 40 mounting that does not move in elevation, of a control valve carried by the slide frame, and hydraulic means for actuating said valve from the aforesaid hand lever.
3. In gun loading apparatus, the combination with the slide frame, the rammer actuating motor carried thereby, and the motor control hand lever mounted on a part of the mounting that does not move in elevation, of a control valve carried by the slide frame, a valve operated by said hand lever, and means for connecting said valve to the control hand valve on the slide frame.

nation with the slide frame, the rammer actuating motor carried thereby, and the motor control hand lever mounted on a part of the mounting that does not move in elevation, of a control valve carried by the slide frame, a valve operated by said hand lever, and means for connecting said valve to the control hand valve on the slide frame.

4. In gun loading apparatus, the combination with the slide frame, the rammer actuating motor carried thereby, and the motor control hand lever mounted on a part of the mounting that does not move in elevation, of a control valve carried by the slide frame, a valve operated by said hand lever, and hydraulic means for connecting said valve to the control valve on the slide frame.

5. In gun loading apparatus, the combination with the slide frame, the rammer actuating motor carried thereby, and the motor control hand lever mounted on a part of the mounting that does not move in elevation, of a differential control valve carried by the slide frame, a pipe supplying constant pressure fluid to said differential valve, a valve operated by said hand lever and a pipe connecting said valve with the differential valve on the slide frame.

6. In gun loading apparatus, the combination with the gun platform, the slide frame, the rammer actuating motor carried thereby, and the motor control hand lever mounted on the gun platform, of a differential control valve carried by the slide frame, a pipe supplying constant pressure fluid to said valve, a valve mounted on the gun platform and operated by the said control hand lever, and a pipe connecting said valve with the differential valve on the slide frame.

In testimony whereof we affix our signatures in presence of two witnesses.
